UNITED STATES PATENT OFFICE

2,569,376

ADJUSTABLE DRAPERY CRANE

Joseph V. Graber, Middleton, Wis., assignor to
The Graber Company, a partnership, Middle-
ton, Wis.

Application February 20, 1950, Serial No. 145,303

2 Claims. (Cl. 211—105.3)

1

This invention appertains to drapery cranes of the type shown in the Graber Patent No. 2,321,196 of June 8, 1943.

One of the primary objects of the present invention is to provide novel means for associating the drapery rod with the swinging crane arm, whereby the rod can be conveniently and quickly adjusted transversely of a window or door opening for different sized openings and for obtaining desired wide or narrow opening effects.

Another salient object of the invention is the provision of an extensible tubular rod with means for adjustably associating the rod with the swinging crane arm by a friction grip, whereby the rod can be moved relative to the crane arm by merely manually releasing the grip, and whereby the use of clamping plates, screws, bolts and the like is entirely eliminated.

A further important object of the invention is the provision of means, whereby the friction grip is entirely hidden within the tubular rod so that a clean streamlined effect will be had and whereby the drapery itself can be conveniently associated with the rod.

A still further important object of the invention is to provide means whereby the friction grip will produce a wide support for the rod so that the tilting thereof on the crane will be eliminated.

With these and other objects in view, the invention consists in the novel construction, arrangement and formation of parts, as will be hereinafter more specifically described and claimed, and illustrated in the accompanying drawing, in which drawing,

Figure 1 is a top plan view of the improved drapery crane, with parts thereof broken away and in section to illustrate structural detail.

Figure 2 is a vertical sectional view through the drapery crane taken on the line 2—2 of Figure 1, looking in the direction of the arrows.

Figure 3 is a transverse detail sectional view, taken on the line 3—3 of Figure 1, illustrating the connection between the swinging crane arm and the attaching bracket.

Figure 4 is a fragmentary longitudinal sectional view taken on the line 4—4 of Figure 2, looking in the direction of the arrows.

Figure 5 is a transverse sectional view taken on the line 5—5 of Figure 1, looking in the direction of the arrows.

Figure 6 is a detail fragmentary horizontal sectional view illustrating the friction lock and showing the same in its released position to permit free sliding of the drapery rod.

2

Referring to the drawing in detail, wherein similar reference characters designate corresponding parts throughout the several views, the letter C generally indicates the improved drapery crane, and the same includes a supporting bracket 10, embodying an attaching face plate 11, and a right angularly outwardly extending leg 12. The bracket is braced and reinforced by pressing out a rib 13 therein. The attaching plate 11, is provide with an opening 14 and slot 15, for the reception of fastening elements 16, whereby the bracket can be conveniently fastened to a window or door casing and the like. The slot 15 permits angular adjustment of the bracket 10 within certain limitations on a wall or casing. Pivotedly secured to the leg 12 of the bracket 10, for swinging movement is the crane arm 17. The crane arm 17 preferably includes like upper and lower companion links 18, and the leg 12 of bracket 10 is received between the links 18 at one end and the links are fastened to the leg by means of a rivet 19. The links 18 can be conveniently stamped from sheet metal and are provided with a marginal bead 20 for rigidity. The outer end 25 of the crane arm 17 pivotally carries and supports a bracket 21 for a drapery rod 22. The rod bracket 21 also includes a vertically disposed leg 25 to which is securely fastened such as by welding or the like, a supporting plate 26, the purpose of which will later appear. It is to be noted, however, that the vertical leg 25 extends about the top and bottom edge of the plate 26, and hence the lower edge of the leg 25 is provided with an inturned flange 27. A part of the flange can be struck up to form a lug 28 which engages the rear face of the plate 26. The opposite ends of the plate have formed thereon resilient gripping legs 29 and the extreme outer ends of the legs are, out-turned as at 30. At the points of juncture of the spring or resilient legs 29 with the plate 26, the same have their upper and lower edges notched as at 31, for a purpose which will also later appear. The spring or resilient legs 29 are received within the drapery rod 22, for a purpose which will now be described.

The rod 22 is of a general tubular shape and preferably, but not necessarily, includes telescoping sections 32 and 33. While, I have stated that the rod is of a general tubular shape, it is to be understood, and as is clearly shown in the drawing, the same is of a C shape in cross section, and hence the inner face thereof is provided with a longitudinally extending slot 34. The resilient legs 29, which in conjunction with the bracket, 50 form a friction grip or locking means for the rod,

are of a considerably greater width than the width of the slot 34, and hence these legs can be introduced into the interior of the rod from one end thereof and the notches 31 formed in the legs 29 receive the longitudinal edges of the rod or walls of the slot 34.

In use the ends 30 of the resilient legs bear against the inner face of the outer wall of the rod and urge the plate 26 outward and the walls of the notches 31 into binding contact with the walls of the slot 34. Thus the rod is held in an adjusted position on the bracket 21 against accidental shifting movement and by pressing in on the rod toward the bracket, the resilient legs will be flexed and the corners of the walls of the notches 31 will be moved away from the walls of the slot 34 and the rod can then be easily slid on the bracket 21. Upon the release of the rod, the resilient legs 29 will again assume their normal position and hold the rod locked on bracket 21 against accidental movement.

My improved drapery crane functions substantially in the same manner, and has the same advantages as the Graber patent heretofore mentioned, with the added advantage that a neat, streamlined effect is obtained and that the rod can be quickly and easily adjusted on the crane without the use of tools, and by merely flexing the resilient legs 29. As the legs lie wholly within the rod the same are hidden from view and a nice appearing rod is had. As the legs project a material distance beyond the bracket 21, these legs form an adequate and firm support for the rod and the rod will not tilt on its bracket 21.

Changes in details may be made, without departing from the spirit or the scope of this invention, but what is claimed as new is:

1. A drapery crane comprising a supporting fixture adapted to be secured to a window and door opening, a swinging crane arm pivotally secured to the fixture, a supporting bracket carried by the outer end of the swinging crane arm, a hollow drapery rod having walls and a longitudinally extending slot on its inner face, and a

friction locking means carried by the bracket including oppositely extending resilient legs received within the hollow rod, said legs having their upper and lower edges at their inner ends reduced in width to receive the walls of the rod, said legs being depressable to release engagement of the legs with said walls of the rod to permit free sliding movement of the rod on the legs and bracket.

2. A drapery crane comprising a supporting fixture adapted to be secured adjacent to a window or door opening, a swinging crane arm pivotally secured to the fixture, a hollow drapery rod having walls and a longitudinally extending slot on its inner face, a bracket pivotally secured to the outer end of the crane arm and including a depending arm portion, a friction locking means including an intermediate U-shaped central body firmly attached to the arm portion of the bracket and resilient outwardly extending legs having their terminals provided with curved feet, said legs being received within the rod and having a width greater than the width of the slot, said legs adjacent to their inner ends being provided with notches at their upper and lower edges receiving the walls of the rod.

JOSEPH V. GRABER.
